UNITED STATES PATENT OFFICE.

JERONIMO CANNON, OF NASHVILLE, TENNESSEE, ASSIGNOR OF ONE-HALF TO BARNEY LEVITAN, OF NASHVILLE, TENNESSEE.

AUTOMATIC TRAIN-STOP SYSTEM.

1,221,968.

Specification of Letters Patent. Patented Apr. 10, 1917.

Application filed October 1, 1915. Serial No. 53,615.

To all whom it may concern:

Be it known that I, JERONIMO CANNON, a citizen of the United States, residing at Nashville, in the county of Davidson and 5 State of Tennessee, have invented certain new and useful Improvements in Automatic Train-Stop Systems, of which the following is a specification, reference being had to the accompanying drawings.

10 This invention relates to means for preventing collisions between railway cars, and particularly to that class of automatic train stop devices in which train pipe pressure is vented in order to apply the air brakes to the 15 car or train, this venting of the pressure in the train line taking place automatically when two cars or two trains are on the same block.

The primary object of my invention is 20 the provision of an automatic train stop mechanism which will prevent head on collisions between trains running in opposite directions on the same track, or prevent collisions between trains running in the same 25 direction on the same track when these trains happen to arrive on the same block.

A further object of the invention is the 30 provision of means whereby electric current may be conveyed from one train to another train on the same block whereby to actuate the brake mechanism on the second-named train, the circuit through the source of energy carried on the first-named train being completed by the arrival of the second- 35 named train on the same block.

Another object is to provide very simple 40 mechanism for latching the vent valve in closed position and to provide very simple electrical mechanism for releasing this vent valve so that it may open to vent the train pressure.

A further object of the invention is the 45 provision of trolleys adapted to be mounted in connection with the railway car, which will engage with conductors disposed beside the track, these trolleys being adjustable so that they may be turned out of position and being mounted so that they will follow and ride along the conductors.

A further object of the invention is to so 50 construct my train stop system that it may be readily applied to prevent trains from running past semaphore signals when the latter are set against the train, and further to so construct the system that it may be 55 used to prevent a train from running through an open switch.

Still another object of the invention is to provide a system which may be applied to cases in which tracks cross each other and 60 provide a system which, in this last case, may be arranged to stop the passage of trains on these intersecting tracks at the point of intersection.

Other objects will appear in the course of 65 the following description.

My invention is illustrated in the accompanying drawings, wherein:

Figure 1 is a diagrammatic view of a section of track having my improved car stop 70 system applied thereto, the cars being shown diagrammatically;

Fig. 2 is a like view to Fig. 1, but showing the application of my system to the stoppage of cars approaching an open switch; 75

Fig. 3 is a like view to Fig. 2, showing my system applied to the stoppage of cars upon the setting of a semaphore signal to danger;

Fig. 4 is a face view of the box or casing within which my mechanism is mounted, the 80 parts being shown in the position taken when the vent valve is open;

Fig. 5 is a section of the box or casing on line 5—5 of Fig. 4 showing the latch mechanism in elevation; 85

Fig. 6 is a section on line 6—6 of Fig. 4 looking toward the magnets 35, the casing being in section;

Fig. 7 is a detail view showing the manner in which the latch engages with the 90 member 15;

Fig. 8 is a detail perspective view showing the end of the latch and of the member 15;

Fig. 9 is an end elevation of a railroad car 95 to show the manner in which the trolleys are mounted;

Fig. 10 is a side elevation of a train of two

cars to show the relative positions of the trolleys normally used and the trolleys on the rear end of the rearmost car used when the train is standing still, the figure showing in dotted lines the different positions of the trolleys;

Fig. 11 is a plan view of the manner of wiring intersecting tracks.

I will first consider the track wiring which is best illustrated in Fig. 1. Referring to this figure, *aa* designates the rails of a single track. On one side of this track there is disposed the conductors 2 and 2^a. These conductors extend parallel to each other and at a suitable distance above the ground and are insulated from the ground in any suitable manner. Each pair of these conductors 2 and 2^a is preferably about five thousand feet long and may be made shorter or longer as the systems and the speed of trains demand. In the figure these conductors are shown as relatively short for an obvious reason. The ends of these conductors 2 and 2^a are supported in non-conducting blocks 1. There is thus normally no electrical connection between these conductors. These pairs of conductors are arranged successively along the entire extent of the track, the ends of one pair of conductors being separated from the ends of the next adjacent pair by a comparatively short space.

On the opposite side of the track there are the pairs of conductors 3 and 3^a which are mounted in the same manner as the conductors 2 and 2^a but are preferably disposed in staggered relation to the conductors 2 and 2^a so that the conductors 3 and 3^a terminate midway between the ends of the conductors 2 and 2^a. Thus the conductors on one side of the track overlap the conductors on the opposite side of the track. Except for the arrangement of the conductors above described and as will be hereafter stated, this is all of the track system of wiring. Normally these conductors are not electrified and therefore are not a source of danger.

It is to be understood that while I will describe a car operating in connection with my system, yet the description applicable to a car, is also applicable to a train, one of the cars of which are equipped with the devices now to be described.

Mounted on each car, preferably in the cab of a locomotive or on the box of the motorman or in any other suitable and convenient position, is a casing designated 4, in which is disposed the mechanism whereby the automatic stoppage of the train is secured as shown in Figs. 4 to 6. Disposed within each box is an electromagnet 5, the free end of whose armature 6 is pivotally connected to a link 7 in turn connected to the upper end of a pivoted arm 8. This arm is pivoted intermediate its ends and the lower

end is pivotally connected to a latch 9. This latch, as illustrated in Fig. 5, is formed with a relatively small neck 10 and an enlarged head 11. Rotatably mounted within the box is a disk 12 which is urged in the direction of the arrow in Fig. 4, by means of the spring 13, this spring being connected to a wrist pin 14 mounted upon the disk 12 and at its other end connected in any suitable manner to a fixed support.

Pivotally connected to the wrist pin 14 is a rod 15 whose end is angularly bent, as at 16, to form a foot, this foot being slotted, as at 17, and formed upon its under face with a recess of such shape as to receive the enlarged head 11 of the latch 9. Pivotally mounted upon a wrist pin 18 projecting from the disk, is a rod 19 which extends out through a slot in the casing and is operatively connected to an arm 20 in turn connected to a vent valve 21 mounted in the vent pipe 22. This pipe is connected to the air brake system in a manner which will be later stated. It will now be obvious that upon an energizing of the magnet 5 the armature 6 will be drawn toward the magnet 9 and this will urge the latch 9 outward away from the magnet, and if this latch is connected to the rod 15 the foot of this rod will also be urged away from the magnet 5 and engaged with the keeper 23, which keeper is mounted upon the side of the box and is in the form of a U-shaped strap of such size as to receive the head 16 on the arm 15. (See Fig. 5.) So long as the magnet 5 is energized the latch 9 will hold the member 15 into latching engagement with the keeper 23. As soon, however, as the magnet 5 is deenergized, the resilience of the armature 6 will cause it to move away from the electromagnet 5, thus drawing upon the latch 9 and this in turn will draw the head 16 out of engagement with the keeper 23, whereupon the spring 13 will cause the rotation of the disk 12 in the direction of the arrow in Fig. 4, the head 16 releasing itself from its engagement with the end of the latch 9. The rotation of the disk 12 under the action of the spring 13 will act to open the valve 21 and allow the pressure within the pipe 22 to be vented through the opening in the valve, thus stopping the train.

The coils of the magnet 5 are connected by means of the members 24 and 25 to binding posts 26 and 27, from which extend wires 28 and 29 to the opposite poles of the battery 30 or other source of electric current. Wires 31 and 32 are also connected to these wires 28 and 29 and extend to shoes or trolleys 33 and 34 which ride upon and have electrical engagement with the conductors 2 and 2^a. It will thus be seen that part of the battery current or current from any other source of current on the car or

train passes through the electromagnets and also passes by way of the shoes or trolleys 33 and 34 to the conductors 2 and 2^a provided the circuit through these conductors is closed 5 as by another car.

The magnet 5 is normally energized, as previously stated, and for the purpose of deenergizing this magnet 5 when two cars arrive upon the same block, I provide within 10 the casing 4 the electromagnets 35. These electromagnets control an armature 36 resiliently held away from the poles of the magnets and this armature in turn carries upon it and movable with it a circuit closing 15 element adapted to close the circuit through the members 24 and 25, and thus short circuits the magnets 5. As illustrated, the armature 36 carries upon it the outwardly projecting stud 37 carrying the cross arm 20 38, this cross arm being of conductive material. It will be noted from Fig. 4 that the conductors 24 and 25 extend from the binding screws 26 and 27 in an outward bow, and that the cross bar 38 is disposed within 25 the bowed portions of these conductors. It will thus be seen that when the magnets 35 are energized the armature will be drawn over to the right in Fig. 6 and this will draw the cross bar 38 in contact with the conductors 24 and 25 and that thus the circuit will 30 be completed through these conductors 24 and 25 and through the cross bar, cutting out the magnet 5 and deenergizing this magnet.

Electrically connected to the magnet coils 35 are the wires 39 and 40 which extend out through the casing 4 and are electrically engaged with the trolleys or shoes 41 and 42 which travel over and have electrical engagement with the conductors 3 and 3^a. It will thus be seen that if there is electrical current in the conductors 3 and 3^a then when the trolleys or shoes 41 and 42 engage these conductors, a circuit will be completed 45 through the wires 39 and 40 to the magnet 35, energizing this magnet. When this magnet is energized it will draw the armature 36 to the right in Fig. 6 and short circuit the wires 24 and 25, thus cutting out the magnet 5, deenergizing this magnet and causing the 50 train pipe pressure to be vented in the manner previously described.

It will be obvious now that when two cars are in the position shown in Fig. 1, one of 55 these cars will be in a closed circuit with the other car, and that the current from the battery on the first named car will be transmitted through the conductors 2 and 2^a to energize the switch magnet 35 on second named 60 car, and that therefore this car will be automatically stopped while the other car will advance until such time as the trolleys or shoes 41 and 42 of first named car engage with or short circuit the conductors 3 and 3^a

with which the trolleys 33 and 34 are engaged. When this occurs both cars will be in the same block and both cars will be stopped automatically until the engineers of the cars reset the apparatus each on his own particular car.

Immediately upon the energizing of the magnet 35 and the deenergizing of the magnet 5 with the consequent release of the member 15 from the keeper 23, the rotation of the disk 12 under the action of the spring 75 13 will carry a contact member or switch 43, into engagement with the wires 39 and 40, closing the circuit across said wires, immediately short circuiting the magnet 5 on the opposite train. As soon as the disk 12 80 has been rotated to close the vent valve and remove the member 15 from the keeper 23, the contact 43 will be taken out of its electrical engagement with the wires 39 and 40, and if the other train is still upon the same 85 block the magnet 35 will be again energized, and it is thus impossible for the engineer to hold the vent valve closed while another train remains on the same block unless the 90 parts are premeditatedly disconnected, or by means of a valve 21^a later described. It will be seen that by this arrangement two trains cannot come within five thousand feet of each other without one of the trains being 95 stopped, and that two trains cannot come within twenty-five hundred feet of each other without both of the trains being stopped. It is, however, obvious, as before stated, that the length of the conductors 2 and 2^a and 3 and 3^a might be increased 100 where trains are running at great speed, so, for instance, that they would be both stopped when they arrived within a mile of each other and one would be stopped if the trains were within two miles of each other, or the 105 blocks might be made relatively short if the speed of the cars was such as not to require a stoppage of the trains at such a distance from each other.

It will be noted from Fig. 4 that the vent pipe 22 is connected to the train pipe of the ordinary air brake system by means of an elbow and that disposed in the pipe 22 between the valve 21 and the train pipe, is a valve 21^a. This valve is normally open but 110 may be closed in order to release the brakes while two trains are on the same block. It will be obvious that the valve 21^a when closed cuts off the vent valve and thus it does not matter whether this valve is open or not because the brakes will be released. This second valve is to be closed by the engineer whenever the train pipe has been automatically vented. It will have to be closed 115 in order to release the brakes when another train is on the same circuit. It should be placed at a point which will be easily reached by the engineer.

In order to prevent rear end collisions, I provide trolleys 44 and 44^a mounted upon the rear car of the train and engaging with the conductors 2 and 2^a and 3 and 3^a. These trolleys may be mounted in any suitable manner as for instance, in the manner in which the trolleys are mounted as illustrated in Fig. 9, and are normally raised, but when the trolleys 41 and 42 and 33 and 34 are raised upon the stoppage of a train, the rear trolleys are depressed into engagement with the conductors 2 and 2^a and 3 and 3^a and short circuit these conductors, and thereby deenergize the magnet 5 on a car C, (see Fig. 1) if the car B be upon the same block.

It will be understood that the front and rear trolleys are not to be used at the same time. The rear end trolley is intended only as an emergency precaution and when down the front trolley must be up, and vice versa.

Not only may my invention be applied to the automatic stoppage of two trains arriving on the same block, but the principle of the invention may also be applied to the stoppage of trains when a block signal or semaphore is set against a train. Thus in Fig. 3 I have shown partially diagrammatically a semaphore mast designated 45, provided with the usual semaphore arm 46, and two contact members 47 and 48 form a circuit closing switch. When the semaphore arm is in its clear position, these contact members are separated or open. When, however, the semaphore arm moves up to danger position, the rear end of the arm will engage with one of the contact members 47 and force it into electrical engagement with the contact member 48, thus closing the circuit through the wires 50 which are connected with the wires 2 and 2^a. It will be obvious that the closing of circuit through the wires 2 and 2^a will short circuit the magnet 5 on the car and applying the brakes in the manner heretofore described.

It is obvious that the same construction may be applied as a means for stopping a train entering or moving toward an open switch. In Fig. 2, 51 designates the rails of the main line and 52 designates switch points. These are operatively connected to an electric switch 53 so that the electric switch will move with the switch points. This switch 53 is connected with a wire 54 leading to the conductor 3^a and coacts with a contact member 55, in turn connected to the conductor 3. When the switch is set for the main line as illustrated in Fig. 2, the circuit through the wires 54 is broken.

The trolleys 41 and 42 and 33 and 34 are mounted so that they are adjustable either into engagement with the respective conductors 2 and 2^a and 3 and 3^a, or out of such position. Any suitable mechanism may be used for this purpose, but as I have illus-

trated in Fig. 9, these trolleys are mounted upon a transverse shaft 56, which is operated by compressed air. The shaft is connected to a piston 57 operating in a cylinder 58, there being a suitable inlet pipe to allow the admission of compressed air to raise the piston and any suitable means for lowering the piston. I have not considered it necessary to go into detail as to this construction as these details will be obvious to any engineer acquainted with compressed air work.

It will be obvious that the principles of my invention may be applied particularly to trains at crossings where one track intersects another track, and that, as shown in Fig. 11, the automatic train stop mechanism will positively stop four different trains approaching the same crossing. In Fig. 11 I show a diagram of such an intersecting track. *a* designates the rails of one track, *b* the rails of the other track, 2 and 2^a and 3 and 3^a designating the conductors for the tracks and 1 the blocks of the insulating material upon which the conductors are supported and which insulates the conductors of one block from the conductors of the adjacent block. The insulating blocks 1 should be disposed all at an equal distance from the intersection of the two tracks and the signal conductors of the tracks *aa* are to be electrically connected to the like wires of the signal conductors of the conductor *bb*, so that a train coming in one direction on the rails *aa* will signal its approach to stop a train approaching and crossing on the rails *bb* in the same manner as heretofore described for trains approaching on the same line of tracks.

It will of course be understood that at the intersection of the tracks, the conductors 2 and 2^a and 3 and 3^a are depressed between the tracks as shown in dotted lines.

The automatic train stop above described will prevent head on collisions between trains running in opposite directions on the same track, and the use of adjustable trolleys permits the suspension of service when a train reaches a section of track not equipped for the same. Furthermore, as above shown, my train stop system will prevent trains running into open switches, or may be used for preventing the running of trains past block signals or semaphores. The maintenance of the system costs practically nothing and the cost of the construction is relatively small. There is no danger from exposed wire circuits as the conductors are not energized unless a train is electrically engaged with the conductors, and even then the voltage will be too light to do much damage, this voltage depending upon whether the current is taken from the source of current for the head light or from storage batteries or from generators driven by the en-

gine. The system is applicable for use with cars driven by steam, electricity or any other source of power, and is obviously also applicable for use with street car systems.

5 It may be employed wherever air brakes are or can be used and to prevent collisions between trains moving on the same track or on different tracks at or near crossings. It will automatically stop and prevent collisions 10 between trains approaching a stalled train from both directions, and may be applied to cases where tracks cross so that trains approaching from opposite directions on both tracks may be stopped and all possibility of 15 rear end collisions with these stalled trains be prevented.

While I have illustrated the details of my construction which I believe to be most effective, I wish it, of course, understood that 20 many changes might be made in these details and in the application of the principle without departing from the spirit of my invention.

While in the specification and in the 25 claims I have used the term vehicle as if all of the apparatus was mounted upon a single vehicle, it is to be understood that by the term vehicle I intend to include a train having any number of cars with the apparatus 30 mounted upon one or more of the cars as I may deem best or as is found most practical in the operation of the invention. It will further be understood that the trolleys 44 and 44^a while preferably mounted upon the 35 rear car of the train, they are also mounted upon the rear end of a single car or vehicle or upon any other portion of the train than the rear.

Having described my invention, what I 40 claim is:

1. In an automatic train stop system, the combination with a track having two pairs of conductors extending alongside thereof and insulated from each other and the 45 ground, of a car traveling over the track having thereon a source of electrical energy, an air brake system on the car including a vent valve, means urging the vent valve to an open position, a latch mechanism holding 50 the vent valve closed against said urging means, an electromagnet having its armature operatively connected with said latching means, said armature when energized holding the latching means in an operative position, 55 means connecting the source of energy in circuit with said magnet and also in circuit with one of said pairs of conductors, a second electro-magnet, means operated by the second electro-magnet for cutting out 60 the first electro-magnet from circuit with the source of energy, and means for connecting the second electro-magnet with the other pair of conductors.

2. In an automatic train stop system, the

combination with a track having two pairs 65 of conductors extending alongside thereof and insulated from each other and from the ground, of a car traveling over the track, an air brake system on the car including a vent valve, a vent valve operating means including a rotatable element operatively connected to the vent valve, a spring urging the rotatable element in a direction to open the vent valve, a member mounted upon the rotatable element, a keeper with which said member is engageable against the action of 70 said spring, an electro-magnet, a latch operatively connected to the armature of said electro-magnet and engaging the said member, the movement of said armature when 75 the electro-magnet is energized causing the release of said member from its engagement with the keeper, a source of energy mounted on the car and electrically connected in circuit with said electro-magnet and with one 80 pair of said conductors, a second electro-magnet connected in circuit with the other pair of conductors, and means actuated by the movement of the armature of the second electro-magnet upon the energizing thereof 85 acting to prevent the passage of current to the first-named electro-magnet to thereby de-energize it and cause the release of said rotatable element and the opening of the vent 90 valve.

3. In an automatic train stop system, the combination with a track having two pairs of conductors extending alongside thereof and insulated from each other and the ground, of a car traveling on the track, an air brake system mounted on the car and including a vent valve, a casing mounted on the car, a rotatable element mounted within the casing operatively connected to the vent valve, a spring urging the rotation 100 of said element in one direction, a keeper mounted on the casing, a member mounted upon the rotatable element and engageable with said keeper to hold the vent valve closed, an electro-magnet including an armature, a latch connected to the armature and adapted to be connected to said keeper engaging member to release it from the keeper upon the energizing of the magnet, a source 105 of energy on the car electrically connected in circuit with said magnet and with one pair of said conductors, a second electro-magnet normally electrically connected to the other pair of conductors and including 110 an armature, means mounted on the armature for preventing the flow of current from the battery through the first-named electro-magnet upon the energizing of the second-named electro-magnet, said means including 115 a conducting member adapted to short circuit the first-named electro-magnet.

4. In an automatic train stop system, the combination with a track having two pairs

of conductors extending alongside thereof and insulated from each other and the ground, of a car traveling on the track, an air brake system mounted on the car and including a vent valve, a casing mounted on the car, a rotatable element mounted within the casing operatively connected to the vent valve, a spring urging the rotation of said element in one direction, a keeper mounted on the casing, a member mounted upon the rotatable element and engageable with said keeper to hold the vent valve closed, an electro-magnet including an armature, a latch connected to the armature and adapted to be connected to said keeper engaging member to release it from the keeper upon the energizing of the magnet, a source of energy on the car electrically connected in circuit with said magnet and with one pair of said conductors, a second electro-magnet normally electrically connected to the other pair of conductors and including an armature, means mounted on the armature for preventing the flow of current from the battery through the first-named electro-magnet upon the energizing of the second-named electro-magnet, said means including a conducting member adapted to short circuit the first named electro-magnet, and means coacting with the rotatable member short circuiting the second-named electro-magnet upon a rotation of said member in a direction to open the valve.

5. In an automatic train stop system, the combination with a track, of a vehicle traveling thereon, an air brake system mounted on the vehicle and including a vent valve, means urging the vent valve to an open position, normally energized means for holding the vent valve in its closed position and normally connected in circuit with a source of energy, conductors extending parallel to the track, trolleys on the vehicle engaging said conductors and disposed in circuit with said source of energy, and means disposed along the track acting to close a circuit through said conductors to thereby short circuit said vent valve holding means to thus release the holding means and permit the vent valve to be opened.

6. In an automatic train stop system, the combination with a track, of a vehicle traveling thereon, an air brake system on the vehicle including a vent valve, vent valve opening mechanism, normally energized means for holding the vent valve in its closed position and normally connected in circuit with a source of energy on the vehicle, conductors extending parallel to the track, trolleys on the vehicle engaging said conductors and disposed in circuit with said source of energy, electrically actuated means mounted on the vehicle normally deenergized but when energized acting to short circuit said vent valve holding means, conductors ex-

tending parallel to the track, and trolleys engaged with said conductors and in circuit with said short circuiting means whereby when the circuit is closed through said last named conductors the short circuiting means will be energized to cause the short circuiting of the vent valve holding means to thereby release the vent valve. 70

7. In an automatic train stop system, the combination with a track, of two pairs of conductors extending along the track, the conductors of each pair being insulated from each other and from the conductors of the other pair, the conductors being divided into blocks, the conductors of one block being insulated from the conductors of the next adjacent block, of trains or vehicles traveling on the track, one of the vehicles of each train having thereon a source of electrical energy and having trolleys connected in circuit therewith and shiftable into engagement with one pair of said conductors, and an air brake system for each train including normally deenergized electrically actuated brake operating mechanism on each train, trolleys connecting said mechanism in circuit with the other pair of conductors and trolleys also mounted upon one of the vehicles of each train shiftable into and out of engagement with the pairs of conductors and when shifted into engagement with said pairs of conductors acting to complete a circuit across said conductors, said last-named trolleys being normally raised from and the first-named trolleys being normally in engagement with the conductors. 80 90 95

8. In an automatic train stop system, the combination with a track and two pairs of conductors extending along the track, the conductors of each pair being insulated from each other and from the conductors of the other pair, of vehicles traveling upon the track, each of said vehicles having means whereby electrical energy may be transmitted to one of said pairs of conductors, and electrical energy received from the other pair of conductors, both of said means being shiftable into or out of engagement with the conductors, an air brake mechanism 105 mounted upon the vehicle and including a normally closed vent valve, electrically actuated means for opening said vent valve and operatively connected to the trolleys which are adapted to receive current from the conductors, and means carried upon the vehicle normally out of engagement with but shiftable into engagement with both of said pairs of conductors for closing a circuit between the conductors of each pair. 110 120 125

9. In an automatic train stop system, the combination with tracks intersecting each other and two pairs of conductors extending parallel to each track, the conductors of each pair on one track being connected to the like 130

conductors of each pair on the other track, and vehicles traveling upon said track, each of said vehicles having means for transmitting electrical energy to one of said 5 pairs of conductors and of receiving energy from the other pair of conductors, an air brake mechanism on each vehicle including a vent valve and electrically actuated means on each vehicle for shifting the vent valve 10 to an open position, and connections where-

by power may be received from one of said pairs of conductors to actuate said vent valve operating mechanism.

In testimony whereof I hereunto affix my signature in the presence of two witnesses. 15
